UNITED STATES PATENT OFFICE

2,468,238

MOUNTING FOR CURTAIN RODS

Santiago Santos, Brooklyn, N. Y.

Application June 3, 1947, Serial No. 752,034

3 Claims. (Cl. 248—265)

1

This invention relates to a support for curtains, portieres, drapes, and the like, and has particular reference to means for adjusting the height of such a support from the floor of the room.

Injuries to persons climbing on chairs or tables or ladders to mount or adjust curtains are frequent and serious. The use of this invention will avert such accidents.

The accompanying drawings illustrate a preferred embodiment, but it is obvious that modifications may be made without departing from the spirit of the invention as hereinafter claimed.

Figure 1 is a front elevation of the new and improved mounting.

Figure 2 is a side elevation thereof.

Figure 3 is a horizontal section taken on the line 3—3 of Figure 2.

Figure 4 is an enlarged horizontal section taken on the line 4—4 of Figure 1.

The curtain or the like is hung on a conventional horizontal curtain rod which is adapted to be hooked on a bracket 11. The drawings illustrate a bracket 11 having two hooks 12 and 14, but it is obvious that more or fewer hooks may be used with equal facility.

The bracket 11 comprises a channel-shaped strip of thin metal, with the hooks 12 and 14 being struck perpendicularly from the central web. The side flanges 16 and 17 of the bracket 11 are in substantially the same vertical planes as the hooks 12 and 14, and the rear portions of the flanges 16 and 17 have inwardly directed angular tabs 18 and 19 that are adapted to slide vertically, as will be described more fully hereinafter, to vary the height of the hooks 12 and 14.

Nested within the channel of the bracket 11 is another channel-shaped plate 20, which, of course, is slightly narrower than the bracket 11 in order to be accommodated therein. The channels of both these members 11 and 20 face the same way. The spacing is sufficient to produce a sliding fit between them as the bracket 11 is moved up or down.

A third channel-shaped base 22 is positioned back of the plate 20, with its channel opposing the channels of the bracket 11 and the plate 20. The flanges of the base 22 are spaced from the flanges of the plate 20 so as to provide a guideway 23 for the flanges 16 and 17 of the bracket 11 during its movement. The plate 20 is fixed, however, with respect to the base 22, and to this end, the flanges of the plate 20 may have one or more struck-out tongues 24 which are clinched to the back of the base 22. Consequently the bracket 11 will be enabled to slide in the vertical

guideway 23 between the flanges of the fixed plate 20 and base 22.

The lower portion of the base 22 may be secured between the arms 26 of a bifurcated wooden or metal holder 27 that is attachable to the stile of a window frame or door frame.

The flanges of the plate 20 are provided with opposed vertical slots to accommodate the angular tabs 18 and 19 of the bracket 11. Consequently, the bracket 11 will be slidable on the plate 20, but will not be dislodged therefrom.

In operation, the curtain is positioned on the rod 10. The bracket 11 is lowered to as low a position as is desired, within the limits of the structure. The rod 10 is then hooked on the bracket 11, and the latter is pushed, by means to be described hereinafter, to the required height, where it will be retained by frictional engagement of the flanges 16 and 17 of the bracket 11 with the mating flanges of the plate 20 and base 22, and by frictional engagement of the channel portions of the members 11 and 20, as well as the tabs 18 and 19 in their slots.

Means, similar to a toggle-link, is provided for moving the bracket to any position within the limits of the device.

This means comprises an upper arm 30 and a lower arm 32, pivoted to each other about a horizontal hinge 33. The bottom of the lower arm 32 is pivoted to the arms 26 of the holder 27 by a horizontal hinge 34. The upper extremity 36 of the upper arm 30 is curved on itself to dovetail with a complementary curved portion 37 of the lower end of the bracket 11, and a pin 38 engages the curved portions 36 and 37 to provide a hinge pivotally connecting the arms 30 and 32.

Both of the arms 30 and 32 are of the same channel and flange dimensions as the bracket 11, so that the flanges of the arms 30 and 32 may be similarly accommodated within the guideway 23 between the base 22 and the plate 20.

The flanges of the base 22 are slightly bulged at 41 to provide a locking cam for the hinge 33 when the arms 30 and 32 are flat against the plate 20. In this position, the cam 41 will frictionally lock the bracket 11 in its uppermost position, as indicated in Figure 1.

The upper arm 30 is made longer than the lower arm 32. When the lower arm 32 is turned 180° from the position shown in Figure 1, and the upper arm 30 is retained in its original direction, the curved portion 36 of the upper arm 30 will be in its lowermost position, and accordingly the bracket 11 will also be in its lowermost position.

By varying the angular posture of the arms 30

2

and 32, the vertical position of the bracket 11 may be controlled between the two limits described.

To assist in manipulating the arms 30 and 32, the upper arm 30 is provided with a handle 42, near the pivot 33.

Figure 2 shows in dotted lines the position assumed by the movable members when the bracket 11 has been lowered from its full-line uppermost position to a position approaching the lowermost position aforesaid.

Any desired movement may be attained by the proper determination of the size of the various members, so that even a child can move the curtain rod to the ceiling.

I claim:

1. In a vertically-adjustable bracket for a curtain rod wherein the bracket is slidably confined in a vertically-disposed base providing a guideway, the improvement comprising a pair of hingedly-connected links providing a toggle, one link including an upper end pivoted to said bracket, the other link including a lower end pivoted to said base, said toggle being extensible to elevate said bracket and collapsible to lower said bracket, and means for locking said toggle with said bracket elevated.

2. In a vertically-adjustable bracket for a curtain rod wherein the bracket is slidably confined in a vertically-disposed base providing a guideway, the improvement comprising a pair of hingedly-connected links providing a toggle, one

link including an upper end pivoted to said bracket, the other link including a lower end pivoted to said base, said toggle being extensible to elevate said bracket and collapsible to lower said bracket, means for locking said toggle with said bracket elevated, and said links being received in said guideway when said bracket is elevated.

3. In a vertically-adjustable bracket for a curtain rod wherein the bracket is slidably confined in a vertically-disposed base providing a guideway, the improvement comprising a pair of hingedly-connected links providing a toggle, one link including an upper end pivoted to said bracket, the other link including a lower end pivoted to said base, said toggle being extensible to elevate said bracket and collapsible to lower said bracket, means for locking said toggle with said bracket elevated, said base being formed with laterally-spaced vertical slots providing said guideway, and said bracket and links being of like channeled configuration providing laterally-spaced vertical flanges receivable in said slots.

SANTIAGO SANTOS.
